Inventor:

William F. Cremeen,

By Parker Cook.

Atty.

UNITED STATES PATENT OFFICE.

WILLIAM F. CREMEAN, OF FRANKFORT, INDIANA.

BRAKE-BEAM HANGER.

1,289,401.

Specification of Letters Patent. Patented Dec. 31, 1918.

Application filed April 1, 1918. Serial No. 225,977.

To all whom it may concern:

Be it known that I, WILLIAM F. CREMEAN, a citizen of the United States, residing at Frankfort, in the county of Clinton 5 and State of Indiana, have invented certain new and useful Improvements in Brake-Beam Hangers, of which the following is a specification.

My invention relates to a new and useful improvement in brake beam hangers and especially to a hanger that may be conveniently used with the standard M. C. B. 10 brake head.

It is well known that after a brake beam 15 has been in use for some length of time, unless some additional support is used, it is apt to tilt, causing a great unevenness of wear of the brake shoe, in fact it often happens that the upper end of the brake shoe 20 will be entirely worn away while the lower half will only be partly worn. The shoe will then have to be scrapped and a new one supplied, which of course means that the shoe has only given half of the service for 25 which it is designed.

Also it often happens that the brake beam will drop if the shoe and key become lost allowing the head to slip from the brake hanger, which is the cause of a great number 30 of derailments.

An object of my invention therefore is to provide a hanger of novel construction that will tend to hold the head in place even though the brake shoe and key should become lost in service, and by holding the head 35 the brake beam will of course likewise be held.

Still another object of my invention is to provide a hanger that will be accommodated by the standard M. C. B. brake head 40 so that no additional work on the brake head is necessary when applying my hanger.

Still another object of my invention is to provide a hanger wherein the auxiliary 45 arm is normally at rest but will come into operation when the brakes are applied and form a truss-like hanger, or support.

Still another object of my invention is to arrange the auxiliary arm so that when in 50 its inoperative position it will still be an additional means for preventing the brake beam and head from falling.

With these and other objects in view my invention consists in certain new and novel 55 constructions and combination of parts as will be hereinafter fully described, and pointed out in the claims.

In the drawings:

Figure 1 is a side elevation of a standard M. C. B. head supported by my improved 60 hanger, the head and shoe being in their normal position;

Fig. 2 is a similar view but the same being moved to the position they occupy when the brakes are applied; and 65

Fig. 3 is a front elevation of the improved hanger.

Referring now to the drawings, a standard M. C. B. head 1 is shown, which has the two openings 2 and 3 therein, and as far 70 as I am aware only one of these openings have heretofore been used for the reception of the brake hanger at the one time. Some of the roads use short hangers to be placed in the opening 3, while others use longer 75 hangers and use the opening 2.

My invention however contemplates the use of both openings at the one time, and I therefore provide two hanger members 4 and 5. The hanger member 4 is substantially U-shaped, being slightly offset or bent near its lower end as at 6, so that it will allow the other hanger member 5 to freely operate in the opening 3. This hanger member 4 normally supports the beam and 80 head, as it will be seen from Fig. 1, that the length of the other hanger member 5 is such that when the head is in the position shown the lower arm 7 of the hanger member 5 is not in contact with the upper wall of the 85 opening 3, but simply swings or idles in the opening, but of course will tend to keep the head from dropping down should the shoe 8 and key 9 be lost or otherwise removed.

Another advantage of a hanger of this 90 kind is that when the brakes are applied and the beam 10 moved forward forcing the head slightly upward, the shorter hanger member 5 will come into operation and move slightly outwardly from the hanger 100 member 4, as clearly shown in Fig. 2. The lower arm 7 will tightly fit against the upper wall of the opening 3, forming a two-point support for the head and the third point of support is by the pin 11 that passes 105 through the eyes in the upper ends of both the hanger members 4 and 5, which pin 11 is supported in a bracket 12, the bracket forming no part of the present invention. This short hanger member 5 of course 110 prevents the upper end of the head from tilting forwardly, which tilting is the cause of the unevenness of wear of the shoe as before mentioned.

This shorter hanger member 5 is also substantially U-shaped, the side arms 13, however, being bent inwardly as at 14 and then again upwardly as at 15 to be supported by 5 the pin 11, the upper end thereof being slightly offset. By bending these arms 14 inwardly the brake head 1 will have to be tilted slightly before the same can be removed, so that this shorter hanger 5 also 10 prevents the accidental loss of the brake head.

Any form of pin 11 may be used, and in the present instance I have shown one that is provided with a slot through which is 15 passed a cotter pin 16 to prevent the loss of the said pin 11 from the bracket 12.

From the foregoing it will be seen that I have devised a brake hanger that is comparatively simple to construct, consisting 20 of but two hanger members of certain shape and length and a pin for pivotally supporting the same. Furthermore, the hanger may be used with any M. C. B. standard head or head that is provided with the two openings 25 2 and 3, and with my hanger it is not necessary to construct or form any special form of brake head. Furthermore, the shorter hanger prevents the objectional tilting of the upper end of the brake head and assists 30 in supporting the brake head and beam when the brakes are applied and the head moved forwardly. It also prevents the accidental loss of the brake head, and if for any reason the larger hanger member 4 should become 35 broken or damaged, the shorter arm 5 will still support the head and beam and prevent the dropping of the same.

I am aware that special forms of brake heads have been constructed with two supporting means and I do not claim such, but 40 what I do claim and desire to secure by Letters Patent is:

1. In combination with a brake head having two openings for the reception of a 45 brake hanger, a brake hanger comprising two hanger members one fitting within each of said openings, one of said hanger members being idle when the head is in its normal position and assisting in supporting the 50 head when the said head is moved forwardly.

2. In combination with a brake head having two hanger openings, a long hanger member in one of said openings and supporting the head at all times, and a shorter hanger member loosely fitting within the other of said openings and supporting the head only when said head is moved in a forward direction.

60 3. In combination with a brake head having two recesses therein for the reception of

a brake hanger, a brake hanger comprising two different lengthened hanger members one in each of said openings, one of said hanger members supporting the head at all 65 times and the other preventing the upper portion of the head from tilting forwardly.

4. In combination with a brake head having two openings for the reception of a brake hanger, two hanger members of different lengths pivoted from the same center and extending into said openings, the hanger of shorter length idling in said opening until the brake head is moved in a forward direction and then forming a truss arrangement with the other hanger to support 70 the said brake head.

5. In combination with a brake head having two hanger openings, two hanger members of different lengths pivoted from the same center and extending into said openings, the hanger of shorter length idling in said opening until the brake head is moved forward and then assisting in the support of said head, said shorter hanger preventing 80 the upper end of the brake head from tilting forwardly and arranged to prevent the brake head from being moved rearwardly off said hanger without first tilting 85 the same upwardly.

6. A brake hanger comprising a substantially U-shaped hanger member, a second hanger member being shorter in length than the first mentioned hanger and means for supporting both of the said hanger members along one central axis.

7. A brake hanger comprising a substantially U-shaped hanger member, said member being slightly offset near its lower end, a second hanger member also substantially 100 U-shaped, and a pin supporting both of said hangers along the one central axis.

8. A brake hanger comprising a substantially U-shaped hanger member and a second hanger member also substantially U-shaped but having its upper arms bent inwardly and then upwardly, and a pin passing through both of said hanger members for supporting the same.

9. A brake hanger comprising a substantially U-shaped hanger member said member being slightly offset near its lower end, a second hanger member being shorter in length than the first mentioned hanger member and having its upper arms bent inwardly 110 and upwardly and the ends of said arms being slightly offset, and a pin passing through the upper ends of both of said hanger members.

In testimony whereof I affix my signature. 120

WILLIAM F. CREMEAN.
